PISTON RING TOOL

Joseph Sunnen, Kirkwood, Mo.

Application September 1, 1932. Serial No. 631,325

13 Claims. (Cl. 29—86.4)

My invention has relation to improvements in automobile mechanics' tools and is particularly directed to a tool for removing and applying piston rings from and to engine pistons, and it 5 consists in the novel features of construction more fully set forth in the specification and pointed out in the claims.

Tools for the handling of piston rings whereby their application to and removal from pistons 10 may be facilitated have heretofore been used, but such tools are either limited for use on a single size of piston ring or if applicable to rings of different sizes have no means for limiting the excessive spreading and resultant distortion or 15 breaking of the ring.

It is the object of the present invention to provide a piston ring tool embodying means for confining the ring as it is expanded to clear the ring lands of the piston, said tool at the same time 20 being adjustable so that it may be applicable to all the common sizes of piston rings in general use in automobile engines, namely from $2\frac{3}{4}$ " to 4" in diameter.

A further object of the invention is to provide 25 the ring tool with a gauge which may be set to the diameter of the piston being operated on so that the confining elements will be spaced the proper distance to permit the rings of the piston to be confined to a degree of expansion sufficient 30 to enable them to be removed from said piston. It is also an object of the present invention to provide a ring tool having a pair of levers engaging the ring ends operable, on account of simplicity, on the order of a pair of pliers. A further 35 object of the invention is to embody in the ring tool means for determining the adjustment of the tool for any size ring with simplicity and certainty so that possibilities of error are practically eliminated. The tool also has the advantage that the rings may be removed from or 40 positioned in any of the grooves of the piston with equal facility. Further and other advantages will be better apparent from a detailed description of the invention in connection with the 45 accompanying drawings, in which:

Figure 1 is a side elevation of my improved tool being applied to the ring in the lower groove of a piston; Fig. 2 is a bottom plan of my improved tool shown in engagement with a piston ring; 50 Fig. 3 is a top plan of my improved tool showing two adjustments of the confining element frame, the diameter of the pistons requiring such adjustments being indicated by the dotted circles; Fig. 4 is a vertical longitudinal section taken on the 55 line 4—4 of Fig. 3; Fig. 5 is a horizontal sectional

detail taken on the line 5—5 of Fig. 4; Fig. 6 is a front elevation of my improved tool shown applied to a piston; Fig. 7 is a diagrammatic view showing the positions of the slots whereby adjustment of the confining elements is effected; and Fig. 8 60 is a diagrammatic view showing the relative positions of one pair of gauge elements and their cooperating confining elements.

Referring to the drawings, B represents what I choose to call the base member of the tool, the 65 same comprising disks 1 and 1' maintained in spaced relation by a rivet 2 and sleeve 3 disposed thereon and spaced rivets 4, 4 and grooved sleeves 5, 5 placed on the rivets 4, 4. A stud 6, polygonal in cross-section, projects upwardly 70 from the base member B, said stud traversing members 1 and 1' and having a sleeve 7 mounted on it between disks 1 and 1'. A pair of levers 8, 8 are disposed between disks 1, 1' on opposite sides of a longitudinal center line a, passing 75 through the rivet 2 and stud 6 (Fig. 5), said levers having perforated lugs 9, 9 disposed in overlapping relation and mounted for rotation on the sleeve 7. The levers 8, 8 are thus pivotally mounted 80 on the base member B and the long arm of each is shaped to comprise a handle H, while the short arm of each lever 8 has a downwardly extending finger 10 provided with a renewable member 11 for engaging the end of the piston ring R (Figs. 1 and 2). The handle part of each 85 lever 8 is channel shaped in cross-section and a U-shaped spring 12 is lodged in said channel with one side 12' of the spring lying in the groove of the grooved sleeve 5, and the other side 12a of the spring terminating in the outwardly bent 90 extremity 12". The springs 12, 12 of the handles H, H maintain said handles in balanced position with respect to the base member B, with their ends carrying the fingers 10, 10 coming together on the center line a under the uniform tension 95 of said springs 12, 12. Obviously, when the handles H, H are grasped in the hand of the operator and pressed together for the purpose of spreading the fingers 10, 10 both the levers will be uniformly actuated with relation to the base 100 member B.

It is quite obvious that the parts thus far described comprise an operative device whereby a piston ring may be expanded if the ends thereof are engaged by tips 11, 11 of fingers 10, 10 and the handles H, H pressed together. However, such a device has no means of preventing excessive stresses on the part of the ring opposite to the gap permitting the ring to be unduly strained and distorted, and occasionally breaking 110

it. In order to prevent excessive stresses on the ring at points that will result in distortion and breaking of the ring, I have provided means for confining the ring at diametrically opposed points 5 while it is being expanded, and thus distribute the expansion uniformly around the ring so it will enlarge circularly. A minimum expansion of the ring will thus permit it to clear the circular ring lands of the piston and easily be 10 moved.

This confining means comprises a frame F embodying two nested members 13 and 14 extending transversely of the levers 8, 8 and mounted on the base member B. In the present in- 15 stance, the members 13 and 14 are channel-shaped, and the sides 15, 15 of member 13 are immediately above the base member B. The sides 16, 16 of member 14 fit snugly over the sides of member 13 so the members 13 and 14 are held 20 in assembled relation by the overlapping sides although they are capable of extension laterally for adjustment to different sizes of pistons. This adjustment is accomplished by slotted connection of the members 13 and 14 with stud 6. In the 25 top plate 17 of member 13 is an inclined slot 18 and in top plate 19 of member 14 is a slot 20 inclined oppositely to slot 18. Thus slots 18 and 20 intersect and the stud 6 passes through both of them.

As explained above, the stud 6 is polygonal in 30 cross-section having four sides, two of which are engaged by the sides of slot 18 and two of which are engaged by the sides of slot 20, so that the assembled members 13 and 14 cannot rotate on 35 the stud 6. The non-rotatable relation of the frame F is preserved with relation to the base member B, because the stud 6 is non-rotatably fixed in the base member, and since the levers 8, 8 are maintained in balanced relation with 40 respect to the base member B the definite transverse relationship between the levers 8, 8 and frame F is also maintained. The maintaining of this relationship between this frame F and levers 8, 9 is important because the frame F car- 45 ries the confining elements for the ring R during the expansion thereof. These confining elements are formed by the inner edges 21, 21 of arms 22, 22 extending downwardly in spaced relation from the end of each of the members 13 and 14.

The arms 22, 22 are slightly wider from the sides 50 of members 13 and 14 downwardly to the shoulders s, s, for the purpose of providing gauge elements 23, 23 whereby the members 13 and 14 may be set to the correct spacing for any size 55 piston rings operated on. It will be observed by referring to Figs. 1, 2 and 6 that the parts of the arms 22, 22 having the gauge elements 23, 23 are more widely spaced than the lower parts of the arms which provide the confining elements 21, 21. The reason for this will be apparent hereinafter.

For the purpose of rigidity, the arms 22, 22 of 60 each pair are connected by screws 24 and spacers 25, as shown (Figs. 1 and 6). The frame members 13 and 14 are held immovably on the stud 6 by means of a wing nut 26 which traverses the threaded reduced end 27 of stud 6, there being a washer 28 disposed over the stud 6 between the outer member 14 and the wing nut. A sleeve 29 65 is loosely disposed over the stud 6 between the inner member 13 and the base member B, and supports the frame F on said base member.

The operation of my improved piston ring tool 70 may be described as follows:

75 We will assume that rings R are to be placed

on the piston P, as shown in Fig. 1. The first operation is to adjust the frame F so that the confining members 21, 21 will be diametrically spaced the correct amount for this ring. This is done by loosening the wing nut 26 so that the members 13 and 14 may be extended or contracted laterally so that on resting the base member B on top of the piston the arms 22, 22 will extend downwardly alongside the piston wall. The operator then slides the members 13 and 14 together until the edges 23, 23 comprising the gauge elements contact with the cylindrical surface of the piston, after which the wing nut 26 is tightened to maintain the arms 22, 22 securely in this particular spaced relation. By referring to Fig. 2 it will be observed that the confining elements 21, 21 extend diametrically beyond the gauge elements 23, 23. But this must needs be, since the position of the gauge elements is fixed with respect to the piston surface, and the position of the confining elements must be fixed with respect to the inner margin of the piston ring which must be expanded sufficiently to pass over the piston surface, or ring lands. Since the confining elements 21, 21 can only operate against 100 the outer margin of the ring, obviously, they must extend diametrically sufficiently beyond the gauge elements to compensate for the ring thickness. When we remember that the thickness of the rings is proportional to the size of the ring 105 and that the present piston ring tool is adapted for all sizes of rings in common use, the position of the confining elements if correct for a large size ring will not be correct for a small size ring unless some means of compensation is found for 110 the error introduced by the variation in ring thicknesses. I have solved this difficulty in the manner illustrated in the diagram shown in Fig. 8 by spacing the confining elements 21, 21 on each side of the ring closer than the spacing 115 of the gauge elements 23, 23. I have obtained the correct location for the confining elements 21, 21 by locating the points of intersection of the outer surfaces of minimum and maximum sized piston rings, for which the tool is designed, 120 while the guide elements 23, 23 are in contact with circles corresponding in diameter with the diameter of the pistons on which these rings are to be used. The diagram (Fig. 8) shows clearly 125 that by locating the confining elements 21, 21 in this manner they are separated the correct distance diametrically for confining against undue expansion any size of piston ring after the tool has been adjusted, as heretofore explained, to the piston receiving the particular ring to be 130 handled.

After the tool has been adjusted, as above described, the operator causes the tips 11, 11 of fingers 10, 10 to engage the ends of the ring R and presses the handle levers together (as shown 135 in full in Fig. 2) until the ring is securely held between the confining elements 21, 21. By referring to Fig. 2 it will be seen that the wider the ring gap is opened the more the ends of the ring will be forced toward the confining edges until 140 the ring has been expanded sufficiently to be passed over the piston and inserted in the ring groove, as shown in Fig. 1. In removing rings from the piston the operation just described is reversed. Instead of expanding the ring to pass 145 the same over the piston it is expanded so that it may be removed therefrom.

By referring to the diagram, shown in Fig. 7, it will be observed that the inclination of the slots 18 and 20, by means of which the frame F 150

- is adjusted, is not 45 degrees as might be expected, in view of the fact that each arm 22, 22 should move outwardly or inwardly from the center of the base member B in an amount equal to the relative movement of the fingers 10, 10 from this center. The diagram shows clearly that the departure from the 45 degree inclination is necessary because the fingers 10, 10 move the distance y along the longitudinal center line a of the tool 10 while the confining edges 21, 21 move the distance x on each side of the transverse center line b . Therefore, the edges 21, 21 for each adjustment have to be moved a greater distance than the fingers 10, 10. I have found that for the positions of the edges 21, 21 the inclination of the slots 18 and 20 should be 42 degrees with the transverse center line b and 48 degrees with the longitudinal center line a . Of course, the inclination of the slots 18 and 20 would change with a change in the positions of the confining edges 21, 21.
- From the foregoing it is apparent that I have provided a tool for expanding piston rings that is easily and quickly adjusted for operation on any size ring in common use, and that is equally effective and operates with equal precision on a ring of any size. In the hands of an experienced operator the chances of breaking a ring while expanding the same are negligible.
- Having described my invention, I claim:
1. A piston ring tool comprising a base member, a pair of levers pivotally connected to said base member, said levers having handles at one side of their pivotal points and means for engaging the ring ends at the opposite side of said pivotal points, and ring confining elements supported by the base member, said elements being disposed in opposition so that a center line through the elements is transverse to the longitudinal axis of the levers, and between the handles and ring engaging means.
  2. A piston ring tool comprising a base member, a pair of levers pivotally connected to said base member, said levers having handles at one side of their pivotal points and means for engaging the ring ends at the opposite side of said pivotal points, and ring confining elements supported by the base member, said elements being disposed in opposition so that a center line through the elements is transverse to the longitudinal axis of the levers, said ring confining elements being interconnected so as to be jointly movable for varying the spacing thereof.
  3. A piston ring tool comprising a base member, a pair of levers pivotally connected to said base member, said levers having handles at one side of their pivotal points and means for engaging the ring ends at the opposite side of said pivotal points, a stem projecting from said base member, a pair of interconnected plates carried by the base member, said plates having oppositely inclined slots traversed by said stem for adjusting said plates in unison, and posts projecting from the ends of said plates.
  4. A piston ring tool comprising a base member, a pair of levers pivotally connected to said base member, said levers having handles at one side of their pivotal points and means for engaging the ring ends at the opposite side of said pivotal points, an adjustable frame carried by the base member, ring confining elements on said frame, and gauge elements on the frame for adjusting the same to effect a spacing of the confining elements according to the piston diameter.
  5. A piston ring tool comprising a base mem-
- ber, a pair of levers for engaging the ring ends, said levers being pivotally connected to said base member, a frame carried by said base member, said frame having elements adapted to confine the ring when the ends thereof are separated by the levers, and means for adjusting the frame laterally and longitudinally with respect to the levers to vary the positions of the confining elements according to the diameter of the ring.
6. A piston ring tool comprising a base member, a pair of levers for engaging the ring ends, said levers being pivotally connected to said base member, a frame carried by said base member, said frame having diametrically opposed elements for gauging the diameter of the piston and diametrically opposed elements for confining the ring when the ends thereof are separated by the levers, the diametrical spacing of confining elements being greater than the diametrical spacing of gauge elements.
7. A piston ring tool comprising a base member, a pair of levers for engaging the ring ends, said levers being pivotally connected to said base member, a frame carried by said base member, said frame having diametrically opposed elements for gauging the diameter of the piston and diametrically opposed elements for confining the ring when the ends thereof are separated by the levers, the location of confining elements being approximately on the outer surface of any given size ring within the range of the tool when the gauge is set to the diameter of the piston adapted to receive the ring of such size.
8. A piston ring tool comprising a base member, a pair of levers pivotally connected to said base member, said levers having handles at one side of their pivotal points and means for engaging the ring ends at the opposite side of said pivotal points, a stem projecting from said base member, a pair of interconnected plates carried by the base member, said plates having oppositely inclined slots traversed by said stem for adjusting said plates in unison, and spaced arms depending from the outer end of each plate, the lower part of each of said arms being offset from the part adjacent to the plate carrying the arm.
9. A piston ring tool comprising a base member, a pair of levers pivotally connected to said base member, said levers having handles at one side of their pivotal points and means for engaging the ring ends at the opposite side of said pivotal points, a polygonal stem projecting from said base member, a pair of interconnected plates carried by the base member, said plates having oppositely inclined slots traversed by said polygonal stem for adjusting said plates in unison, and posts projecting from the end of said plates.
10. A piston ring tool comprising a base member, a pair of levers pivotally connected to said base member, said levers having handles at one side of their pivotal points and means for engaging the ring ends at the opposite side of said pivotal points, a stem projecting from said base member, a pair of interconnected plates carried by the base member, said plates having slots traversed by said stem, said slots being inclined approximately 45 degrees to effect longitudinal and lateral adjustment of said plates simultaneously, and posts projecting from the ends of said plates.
11. A piston ring tool comprising a base member, a pair of interconnected plates carried by said base member, ring confining elements disposed in opposition on said plates, said plates being mounted for joint movement to vary the

spacing of said confining elements, and means for expanding the piston ring into contact with the confining elements.

12. A piston ring tool comprising a base member, a suitable frame carried by and extending across said base member, posts projecting from the ends of said frame, means for jointly moving said posts to vary the spacing thereof, and means for expanding the ring into contact with

10 the posts.
